CLAIM

The ornamental design for a motorcycle fuel tank cover as shown and described.

DESCRIPTION

FIG. 1 is a front-left side perspective view of a motorcycle fuel tank cover embodying our new design;

FIG. 2 is a rear-right side perspective view thereof;

FIG. 3 is a left side elevation view thereof;

FIG. 4 is a right side elevation view thereof;

FIG. 5 is a top plan view thereof;

FIG. 6 is a front elevation view thereof; and,

FIG. 7 is a rear elevation view thereof.

The broken lines in the drawings illustrate portions of the motorcycle fuel tank cover and the environmental tank structure, which form no part of the claimed design.
